UNITED STATES PATENT OFFICE.

ALRAH B. EDWARDS, OF ABILENE, TEXAS.

DESIGN FOR A HOSE-WINDING-MACHINE CASING FOR USE AT FILLING STATIONS,
GARAGES, AND OTHER PLACES.

Application filed April 7, 1927. Serial No. 21,500. Term of patent 7 years.

To all whom it may concern:

Be it known that I, ALRAH B. EDWARDS, a citizen of the United States, residing at Abilene, in the county of Taylor and State of Texas, have invented a new, original, and ornamental Design for Hose-Winding-Machine Casings for use at Filling Stations, Garages, and Other Places, of which the following is a specification, reference being had

to the accompanying drawing, forming a part thereof, in which the figure is a perspective view of the article showing my new design.

I claim:

The ornamental design for a hose winding machine casing for use at filling stations, garages, and other places, as shown.

ALRAH B. EDWARDS.
